DESIGN FOR A TEXTILE FABRIC

Oscar J. Cahn, New York, N. Y.

Application February 27, 1936, Serial No. 61,377

Term of patent 3½ years

To all whom it may concern:

Be it known that I, Oscar J. Cahn, a citizen of the United States, residing at New York city, county and State of New York, have invented a new, original, and ornamental Design for a Textile Fabric, of which the following is a specification, reference being had to the accompanying drawing, forming part thereof.

The figure is a plan view of a textile fabric showing my new design.

The design consists of a series of groups of sinuous lines embodying nub-like threads, each group comprising spaced-apart stripes graduated in size, the surface of the fabric being penetrated by hairs.

I claim:

The ornamental design for a textile fabric substantially as shown and described.

OSCAR J. CAHN.
